UNITED STATES PATENT OFFICE.

GEORGE A. STANBERY, OF ZANESVILLE, OHIO.

TILE-PRESS.

SPECIFICATION forming part of Letters Patent No. 388,926, dated September 4, 1888.

Application filed July 29, 1887. Serial No. 245,595. (No model.)

To all whom it may concern:

Be it known that I, GEORGE A. STANBERY, a citizen of the United States, residing at Zanesville, in the county of Muskingum and State of Ohio, have invented certain new and useful Improvements in Tile-Presses; and I do hereby declare that the following is a full, clear, and exact description of the invention, which will enable others skilled in the art to which it appertains to make and use the same.

The press herein shown and described is designed more especially for compressing encaustic tiles; but it may also be employed in the manufacture of other kinds of earthenware without material departure, if any, from the structure herein shown and described.

In the presses heretofore used there were two plungers, the lower of which supported the earth or clay in the die and the upper plunger was brought down upon the lower one by means of a long threaded screw to do the pressing. This screw was operated by a lever which might be weighted, and, being controlled by hand, was run down as forcibly as possible and then up and down again, and this action was repeated several times until the air was expelled from the material by the blows thus delivered and the tile compressed to the desired thickness and density. When this result was accomplished, the top plunger was run up out of the way and the lower plunger forced up by foot-power to expel the tile from the mold. Other forms of press than the one here described are known; but this press was the most commonly used of any within my knowledge, and may be said to illustrate the state of the art as practiced up to the time of my invention.

Several disadvantages attended the manufacture of tiles by the old method or press, which it has been my purpose in this invention to remedy. In the first place, it required too much hard manual labor; secondly, it was too slow, and, as the pressing was done by hand, it was liable to be uneven and irregular; thirdly, it was difficult to get the tile from the mold or die without its being buckled or warped. The repeated blows by which the pressing is effected are designed as well to expel the air from the clay; but as all the air cannot be expelled there is a natural tendency in the pressed material to expand when

the pressure is relieved; hence in the old machines when the tile is in the mold and held from expansion laterally and the top plunger is raised there is relief upward which the tile is apt to seek and buckling follows. These and other difficulties and objections were encountered in the old machines, which it is my object to remedy and are remedied in this machine.

Referring to the drawings, Figure 1 is a perspective view of my improved press, showing it ready for operation. Figs. 2 and 3 are side elevations showing opposite sides thereof. Fig. 4 is a vertical section, enlarged, of the table, lower plunger, and die, and the mechanism for raising and lowering the said plunger automatically. Fig. 5 is a front elevation of the upper part of the machine, showing the mechanism for starting the press and for regulating the number of strokes of the upper plunger. Fig. 6 is a transverse section of the operating-shaft, line XX, Fig. 2, showing the cam thereon and the lever operated thereby, and seen to the left, Fig. 2, said lever being connected through the vertical rod shown in this view with the mechanism for automatically raising the lower plunger simultaneously with the upper one when the pressing is completed. Fig. 7 is a vertical transverse section of the cross-head on the line of the main shaft, showing the crank for operating the upper plunger. Fig. 8 is an enlarged detail of the mechanism (shown at the bottom of Fig. 1) for automatically operating the lower plunger. Figs. 9, 10, 11, 12, and 13 are details of elements shown in Fig. 5, and more particularly referred to and described hereinafter. Fig. 14 is a cross section showing the guides in the cross-head.

In the drawings, A represents the base of the press. Upon this are supported the standard *a* at its rear and the two rod-shaped standards, *a' a'*, at the front. These standards may be secured to the base in any way that will give them strength and solidity.

B is a cross-head, formed in two sections, firmly bolted on the standards or posts *a' a'* by bolts *b*, and provided with a bearing for one end of the shaft C, while the other end is supported on the standard *a*. A fly band-wheel, C', is loosely mounted on the outer end of the shaft C, and inside thereof is a clutch, *c*,

Fig. 3, operated by a lever, c' , extending to the front of the machine in convenient reach of the pressman.

The press proper may be said to consist of two opposite plungers, the upper of which, D, Fig. 7, is connected by means of a forked connecting-rod, D', with a crank, d, on the main shaft C. A recess or open space is formed between the respective sections of the cross-head, as seen in Fig. 7, within which the crank for operating the plunger D is located, the shaft C having bearings in the two sections, as there shown.

Beneath the cross-head, and attached to the posts a' a' , are a pair of guides, E E, for the plunger D. (Shown in cross-section in Fig. 14.)

In the operation of the machine, as before stated with reference to the old machines, it is desirable to deliver or effect a succession of blows upon the material in the mold or die, which impact and compress the material and at the same time expel the air therefrom. This action is here obtained from the shaft C through the crank d and the plunger D working in its guides. So far no adjustment has been provided for, and the means to regulate the thickness of the tile will be described further on. Now, it is desirable to regulate and fix the number of blows delivered to the material, so that they may be determined automatically, as well as to employ positive mechanism instead of hand-labor in effectuating the blows. This is accomplished through the mechanism shown most clearly in Fig. 5 and the group of details about it.

The main shaft is operated when the clutch c is in engagement with the wheel C'. I have arranged to disengage the clutch and stop the wheel when as many strokes of the plunger D are made as shall be needed, according to the material used or other conditions not material to mention here. Thus I have attached to the cross-head B a hanger, F, having a vertical slot, f, and set-screw f' at the upper end of the slot. Pivoted to this hanger is a bell-crank lever, G, having an adjustable weight, g, and a point, g', above its pivot, on which the lever c' rests when the clutch is in engagement. The lever is held by the bell-crank G until it is released by arm H, fixed pivotally on the hanger I, pendent centrally from the cross-head, and having a horizontal bolt, i, in its lower portion, which the arm H is arranged to strike, and which, when struck and moved by said arm, will swing the bell-crank forward (see dotted line, Fig. 5) and release the clutch-lever, thereby stopping the driving-wheel. Above the arm H and integral therewith is a segment, h, having a series of teeth, h', which are arranged to be engaged by a finger, K, on a sleeve, K', on the extremity of shaft C. At each revolution of said shaft the finger K will strike one of the teeth h' and move the segment forward one notch, thus bringing the arm H that much nearer the bell-crank G. Perforations i' are shown in hanger I, by which the

segment and arm may be set to start at any desired notch or tooth in the series h' , which will determine the number of strokes made by the upper plunger before it stops, each tooth representing one revolution of the shaft C, and consequently one stroke. For minute adjustment of the arm H with reference to its stroke, a set-screw, h^2 , may be fixed in its end at the point of contact with the rod i .

Obviously the action upon the clutch sought and accomplished by the mechanism here described may be widely varied and yet remain within the spirit and purpose of this part of my invention, the essential point being to automatically determine and control the strokes of the upper plunger with respect to their number and the time of stopping the same.

The lower part of the press is shown in vertical section in Fig. 4. First we have a heavy cast bed-piece, M, (shown also in Fig. 1,) which has set centrally therein a hard-metal screw-threaded thimble, L. Within this thimble is an internally and externally screw-threaded sleeve or tube, N, which extends both above and below the thimble and casting M, and at its lower end has a band, n, with a lever, n' , attached thereto, and a hand-lever, n^2 , near its top. (Seen clearly in Figs. 1 and 3.)

Within the sleeve N is an externally-threaded sleeve, O, having a hand-wheel, o, at its lower extremity, by which said sleeve is raised or lowered. The head of the plunger L' is spread to cover the upper end of the sleeve O, while the stem of the plunger extends down through the center thereof and some distance below. Three separate movements are obtained by this construction.

First, to fix the thickness to which the tile is to be compressed, the sleeve O of the lower plunger may be adjusted higher or lower according to the thickness wanted. It will be observed that the lower plunger-head also serves as the bottom of the mold.

Secondly, the outer sleeve, N, is adjustable by means of handle n^2 , which is designed for raising the lower plunger with its support O slightly after each stroke of the upper plunger, so as to feed the tile gradually to the upper plunger as the material is compressed by each successive blow. This movement by sleeve N is by hand, and, as seen in Fig. 1, may be fixed within regular limits indicated by pins or posts p p , which may be set in any one of the holes p' , and thus shorten or lengthen the range of the lever. Upon the main bed M, and about the upper end of the lower plunger and its inclosing sleeves, is a short cylinder, Q, which is screw-threaded exteriorly and has adjustable thereon another short cylinder, Q', having a hand-wheel, q, for operating it. Upon the latter cylinder is a table, R, which in turn supports the die S and a feed-plate flush with the upper surface of the die. This construction enables me to fix the depth of the mold, and consequently the quantity of material it will hold. When the last notch in segment h , Fig. 5, has been reached and the press is about

to be stopped by the dropping of the clutch-lever, it is understood that the operator will have carried the lever n^2 around to its limit at the right of the base-plate and against the post p thereon. This movement of the sleeve N by means of lever n^2 will also carry lever n' around to the right, so that it will occupy the position shown in dotted lines, Fig. 1.

Here we approach the mechanism by which 10 the lower plunger is automatically elevated to the level of the die and feed-plate simultaneously with each final upward movement of the upper plunger, and in such relation to said plunger that the tile is held firmly between the 15 two plungers until after it leaves the die or mold.

It has been stated that the old machines were defective and unsatisfactory, for the reason that the tiles were liable to become injured 20 by expanding upwardly and buckling while yet in the die after the upper plunger was withdrawn. This was a material and serious defect, which I have overcome by the mechanism here described. Some expansion will 25 in all cases occur, however perfectly the machine may operate; but by holding the tiles between the plungers and at the same time removing them from the die the expansion occurs laterally or edgewise, and not upon the 30 face, which can work no injury, and buckling or bending is absolutely prevented. I have therefore constructed my machine to automatically hold and raise the tile between the plungers with each final upward movement of 35 the upper plunger, and the further mechanism by which this result is accomplished is as follows: Journaled in the lower part of the base, Fig. 1, is a shaft, T , which at its center is shown as having an arm, t , which connects 40 by a yoke, v , with trunnions v' on a nut, v^2 , on a screw-threaded portion of the stem of the lower plunger. This thread is cut reversely to the thread on the outside of sleeve O , so that the nut v^2 will remain stationary through the 45 adjustments of sleeve O and said plunger. To the right on shaft T , Fig. 1, is a loose bell-crank, w , which connects by a long rod, w' , with a lever, X , Fig. 5, pivoted at its opposite end upon the cross-head, and having a 50 sheave, X' , at its center, which is engaged by a cam, Y , Fig. 6, on the main shaft. This cam and the crank are so arranged on the main shaft that both will act to raise the respective plungers together and at the proper time. By 55 the side of the bell-crank w on shaft T is fixed an arm, v^3 , in the end of which is a spring-pressed bolt, v^4 . When the lever n' is carried around to the extremity of its movement, it presses the spring-bolt through till it engages the arm of crank w . The movement of 60 this crank will then be imparted to arm v^3 and shaft T , and the lower plunger raised to the desired height at the proper time, as before described. A hand-lever, Z , is attached to 65 one end of shaft T , and to avoid breakage resulting from possible misadjustment of the

parts a safety-spring, w^3 , with a tightening-nut, w^4 , is placed on the upper extremity of rod w' .

It is desirable that shaft C should cease rotating as soon as the clutch c is released from the drive-wheel. To accomplish this result, I place a pulley, c^2 , on the shaft which is engaged by a brake, c^3 , pivoted on the standard a and weighted to get the desired effect. 70

It has been observed that after certain movements have been made and the desired pressing of the tile is obtained the lower and upper plungers rise together and hold the tile between them. When this occurs, the power is at the 80 same instant shifted from the drive-shaft, and then the friction-brake asserts itself and stops said shaft the instant the power is removed, so that there will be no further movement of the upper plunger and the tile remains between the two plungers. This friction-brake is relied on to prevent the rotation of the main shaft when the power is removed therefrom and is indispensable for this purpose. The weight on the brake lever should be sufficiently heavy to act promptly on the shaft. 85 A brake, 10, Fig. 3, likewise is attached to the frame A , and engages a segment, 12, on shaft T to hold said shaft and its attachments in the position to which they are carried by 90 the action of bell-crank w on arm v^3 , the lower plunger in this case being raised to clear the die. 95

In case it is desired or becomes necessary the shaft T may be operated by hand-lever z and 100 the lower plunger thereby raised, and this lever is also useful in lowering said plunger to its starting-point after each upward movement.

I have shown and described one way or one 105 special set of mechanical devices for accomplishing the objects of my invention; but it is clear that other devices or means, bearing no resemblance to these except in function, might be substituted and do the work as well. I do 110 not, therefore, consider my invention limited by the special appliances here shown and described, but regard it broad enough to cover other forms or combinations of mechanism the equivalents of these, and which have substantially similar functions, or accomplish the 115 same or similar results however different in appearance or arrangement. For example, the means of effecting the various movements and adjustments of the lower plunger alone 120 or in conjunction with the upper plunger are susceptible of infinite variation, as any mechanician skilled in this art will readily see. The same is true of the mechanism embodied in the other parts of my machine, modifications 125 or different forms of which are readily suggested.

The operation of the press will be understood from the foregoing specification, and need not be more particularly or fully described. 130

Having thus described my invention, what I

claim as new, and desire to secure by Letters Patent, is—

1. In a tile-press, a main shaft having a plunger mounted eccentrically thereon, and a shifting device to throw the plunger in and out of operation, said shifting device having a lever or arm to move it, in combination with an arm operated by the main shaft and constructed to release the said lever after two or more revolutions of the shaft, substantially as set forth.

2. In a tile-press, a main shaft, a plunger mounted on said shaft, a shifting device connected with said shaft to hold or release the same with reference to the driving-power, a projection on said shaft, and mechanism between said shaft and the shifting device consisting of a lever, a catch for the lever, and a moving arm to automatically move the shifting device and to vary the number of strokes delivered by the plunger, substantially as set forth.

3. In a press, a reciprocating plunger, a drive-shaft, an arm operated by the drive shaft and adjustable in respect thereto, a shifting-lever to stop the movement of the shaft, and a catch for the lever operated by said arm, substantially as set forth.

4. In a press, a main shaft having a projection on its end, and a notched arm pivoted to be engaged by said projection, a clutch for the shaft having a lever, and a catch for the lever movable by said arm, substantially as set forth.

5. In a press, a main shaft having a drive-wheel loosely mounted thereon and a clutch between said parts, in combination with a lever for the clutch, and an arm adjustable in respect to the shaft and engaged by a projection thereon, whereby the said part is moved to release the said lever from its catch after any predetermined number of revolutions of the shaft, substantially as set forth.

6. In a press, a main shaft having a lateral projection, an arm with notches engaged by said projection, said arm being adjustable to bring one or another of the notches into engagement with the projection, a reciprocating plunger, and a lever and clutching device automatically operated by the aforesaid arm, whereby the number of strokes delivered by the plunger is regulated, substantially as set forth.

7. In a press, a shaft having a plunger mounted to be reciprocated thereby, a band-wheel, a clutch to lock the shaft with the band-wheel, and a lever to operate the clutch, in combination with a pivoted and adjustable arm having notches engaged by the said shaft through a projection thereon, and a rod operated by said arm to disengage the clutch-lever, substantially as set forth.

8. In a press, a main drive shaft, a reciprocating upper plunger, a shifting device to disengage the shaft from the driving power, and a brake for the shaft, whereby the movement

of the plunger is summarily stopped, substantially as set forth.

9. In a press, the main shaft having a lateral projection, a fixed arm below the shaft, a pivoted arm on the fixed arm having notches engaging the projection in the shaft and adjustable on the fixed arm to bring any one of said notches into initial engagement, a shifting-lever for the main shaft, and a rod on the fixed arm for releasing said lever, substantially as set forth.

10. In a tile-press, a main shaft having a plunger mounted eccentrically thereon, a device to engage the shaft with the driving-power, and a lever to operate said device, in combination with a pivoted piece engaged by a projection on the main shaft and constructed to be moved forward step by step with each revolution of said shaft, and a rod and catch for the aforesaid lever operated by said pivoted piece, substantially as set forth.

11. In a press, a crank-shaft, a plunger attached to the shaft, and power-connections on the shaft, whereby a regular and constant reciprocating movement is imparted to the said plunger while the pressing is being done, in combination with a lower plunger, and a sleeve and lever for raising said lower plunger and gradually lifting the material in the die as it is pressed by the action of the upper plunger, substantially as set forth.

12. In a press, an upper plunger, and a lower plunger vertically adjustable by means of a screw sleeve surrounding said plunger, and a second sleeve outside said screw-sleeve with a handle to operate it, substantially as set forth.

13. In a press having two plungers set opposite each other, a lower plunger set within adjusting-sleeves by which the elevation of the plunger is regulated, and independent levers for adjusting said sleeves, substantially as set forth.

14. In a press having opposite plungers, a main bed, as M, a thimble, as L, and two adjusting-sleeves, as N O, with a plunger inside the sleeves, substantially as set forth.

15. In a press, a main bed, as M, a short cylinder, as Q, and a second cylinder, as Q', adjustable vertically to change the depth of the mold, substantially as set forth.

16. In a press, an adjustable sleeve, and a plunger having a head resting in said sleeve, in combination with a short cylinder about the mold adjustable to vary the depth of the mold, substantially as set forth.

17. In a press, a lower plunger surrounded by an adjusting-sleeve to raise or lower the plunger, in combination with an arm for raising the plunger independent of the sleeve, said arm being operated from the drive-shaft, substantially as set forth.

18. In a press, a lower plunger and a rock shaft and arm for raising said plunger, said rock-shaft having a lever for operating it brought into engagement by a projection on

a sleeve surrounding the lower plunger, all in combination, substantially as set forth.

19. In a press, a lower plunger surrounded by a sleeve having a lever, a shaft and arm to raise the plunger, and a second arm on the shaft to make connection with the mechanism, extending to the drive-shaft, all in combination, substantially as set forth.

20. In a press, a rock-shaft to raise the lower plunger provided with a fixed arm and a pivoted lever, a lever on a sleeve about the plunger to move the fixed arm and pivoted lever into engagement, and a rod connecting the pivoted lever with the drive-shaft, all in combination, substantially as set forth.

21. In a press, a rod connected with an eccentric on the main shaft and a rock-shaft operated by said rod, in combination with a sleeve for adjusting the lower plunger and a lever on said sleeve to bring the rock-shaft into rigid engagement with the rod extending to the main shaft, all in combination, substantially as set forth.

22. In a press, a rock-shaft having a rigid arm pivotally connected with the lower plunger, a bell-crank on the end of the shaft, an arm on the shaft to engage the bell-crank, a screw-sleeve around the said plunger, and a lever on said sleeve to bring the bell crank into engagement with the arm at its side, all in combination, substantially as set forth.

23. In a press, a reciprocating plunger provided with mechanism for varying the number of blows, in combination with a lower plunger and an independent lever and sleeve for raising said plunger while the upper plunger is at work, substantially as set forth.

24. In a press, an upper plunger eccentrically connected with the main shaft and a lever and operated from said shaft and controlling a clutch thereon, said arm constructed to vary the number of blows to be delivered by the said plunger, in combination with a lower plunger and a hand-lever to raise the same, all in combination, substantially as set forth.

25. In a press, a main shaft and an adjustable device connected therewith and constructed to regulate the number of successive revolutions of said shaft, a lever operated by said device, said lever controlling a clutch on the shaft, in combination with a lower plunger raised by a lever independent of the main shaft, substantially as set forth.

26. In a press, a main shaft and a plunger thereon, and an arm controlled by said shaft

having notches whereby the number of successive blows of the plunger are varied, a clutch engaging the shaft with the drive power, and a lever to operate the clutch, in combination with a lower plunger having a screw-sleeve to raise it while the upper plunger is at work, substantially as set forth.

27. In a press, an upper plunger, an adjustable arm operated by the main shaft, and a lever and clutch operated by said arm, whereby the plunger is stopped at a predetermined point after one or more blows of the plunger, in combination with a rock-shaft connected with the lower plunger and operated from the main shaft to raise the lower plunger when the upper plunger stops, substantially as set forth.

28. In a press, a reciprocating upper plunger and a shaft-controlling mechanism whereby said plunger is stopped after one or more revolutions of the shaft, said mechanism consisting, essentially, of a notched arm engaging with said shaft, and a lever and clutch operated thereby, a lower plunger having a sleeve and lever to raise it, and a rock-shaft for raising the lower plunger with the last upward movement of the upper plunger, substantially as set forth.

29. In a press, a reciprocating upper plunger and a lower plunger automatically raised with the last upward movement of the upper plunger, in combination with a brake on the main shaft, substantially as set forth.

30. In a press, a main shaft, a reciprocating upper plunger, and a brake for said shaft to suddenly stop the same, in combination with a lower plunger connected with a rock-shaft to raise it, and a brake for said rock-shaft, substantially as set forth.

31. In a press, a lower plunger having a screw-sleeve for raising and lowering it, a handle on said sleeve, and an adjustable stop for said handle, whereby said sleeve may be fixed to start in its rotations from any desired point, substantially as set forth.

32. In a press, a reciprocating upper plunger, in combination with a lower plunger provided with a lever and sleeve for gradually raising the lower plunger while the upper plunger is at rest, substantially as set forth.

In testimony whereof I hereunto set my hand. 105
